UNITED STATES PATENT OFFICE

117,366

DESIGN FOR A NOVELTY PIN OR SIMILAR ARTICLE

Max Genser, Providence, R. I., assignor to Genser Manufacturing Co., Providence, R. I., a firm composed of Max Genser and David Genser

Application August 30, 1939, Serial No. 86,968

Term of patent 3½ years

To all whom it may concern:

Be it known that I, Max Genser, a citizen of the United States of America, residing at Providence, county of Providence, State of Rhode Island, have invented a new, original, and ornamental Design for a Novelty Pin or Similar Article, of which the following is a specification, reference being had to the accompanying drawing, forming a part thereof:

Fig. 1 is a front elevational view of a novelty pin showing my new design; and

Fig. 2 is a side elevational view thereof.

I claim:

The ornamental design for a novelty pin or similar article, substantially as shown.

MAX GENSER.
